UNITED STATES PATENT OFFICE

131,679

DESIGN FOR A BABY'S HIGH CHAIR

Bernard Greenbaum, New York, N. Y.

Application September 30, 1941, Serial No. 103,558

Term of patent 7 years

To all whom it may concern:

Be it known that I, Bernard Greenbaum, a citizen of the United States and a resident of the city of New York, in the county of New York and State of New York, have invented a new, original, and ornamental Design for a Baby's High Chair, of which the following is a specification, reference being had to the accompanying drawings, forming a part thereof.

Fig. 1 is a front perspective view of a baby's high chair, showing my design; and

Fig. 2 is also a front perspective view but with the table illustrated as it would appear in the extended position.

Fig. 3 is a rear perspective view upon a reduced scale of the upper portion of the high chair back with parts of the chair broken away.

I claim:

The ornamental design for a baby's high chair, substantially as shown.

BERNARD GREENBAUM.
